U.S. Appl. No. 29/704,013, filed Aug. 30, 2019.

Primary Examiner — T Chase Nelson(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side rear perspective view thereof;

FIG. 5 is an opposite side view thereof;

FIG. 6 is an opposite side front perspective view thereof;

FIG. 7 is a front perspective view of an alternative embodiment of a shoe showing my new design;

FIG. 8 is a side view thereof;

FIG. 9 is a rear perspective view thereof;

FIG. 10 is an opposite side rear perspective view thereof;

FIG. 11 is an opposite side view thereof; and,

FIG. 12 is an opposite side front perspective view thereof.

The broken lines immediately adjacent to the shaded area define the bounds of the claimed design and form no part thereof. In FIGS. 1-6, the oblique line shading represents a transparent or translucent appearance. The broken lines depicting the remainder of the shoe show features that form no part of the claimed design.
